UNITED STATES PATENT OFFICE.

GEORGE S. GATCHELL, OF ROSELLE PARK, NEW JERSEY, ASSIGNOR TO THE SINGER MANUFACTURING COMPANY, OF ELIZABETH, NEW JERSEY, A CORPORATION OF NEW JERSEY.

NEEDLE-LOOP SEPARATOR FOR SEWING MACHINES.

Application filed February 3, 1920. Serial No. 356,008.

To all whom it may concern:

Be it known that I, GEORGE S. GATCHELL, a citizen of the United States, residing at Roselle Park, in the county of Union and State of New Jersey, have invented certain new and useful Improvements in Needle-Loop Separators for Sewing Machines, of which the following is a specification, reference being had therein to the accompanying drawings.

This invention relates to needle-loop controllers for sewing machines and has for a primary object to provide means applicable more particularly to multiple-needle single-looper sewing machines for preventing the newly formed needle-loops from twisting around sidewise as they are thrown out by the needles and are about to be seized by the advancing looper. Stated in another way, the invention has for an object to provide means for holding the newly formed needle-loops in spaced parallel planes transverse to the path of the advancing looper, so that the looper will enter the needle-loops with certainty.

A further object of the invention is to provide means for overcoming the tendency of the looper to drag a previously seized needle-loop into an adjacent loop which is about to be seized; such action causing the needle-loops to be crossed on the looper.

In accordance with the present invention, a loop-controlling element in the form of a multi-toothed comb is mounted on the feed-dog of the machine; the comb being positioned in rear of the needles with its teeth projecting toward the needles or in a direction opposite to the direction of feed. The teeth of the comb are spaced apart a distance equal to the distance between adjacent needles and the arrangement is such that when the feed-dog moves forward preparatory to rising into engagement with the work, the teeth of the comb are projected forwardly between the needles, so that when the needles rise and throw out their loops, the teeth act to guide the expanding loops and prevent their twisting sidewise out of the path of the advancing looper.

When the looper has seized the needle-loops and the feed-dog executes its feeding stroke, the teeth of the comb are withdrawn from their positions between the needle

paths, in order that the needle-loops shed from the looper during a later stage of the stitch-forming cycle may be drawn up to the work without catching on the comb. An auxiliary guard may be utilized to cover the teeth of the comb when the latter is in retracted position.

In the accompanying drawings, Fig. 1 is a side elevation illustrating the essential elements of a sewing machine embodying the invention. Figs. 2, 3 and 4 are details of the feed mechanism of the machine. Fig. 5 is a plan view of the work-supporting arm and feed mechanism incorporated therein; the standard of the machine being shown in horizontal section. Figs. 6 and 7 are cross sectional views on the lines 6-6 and 7-7, respectively, Fig. 5. Fig. 8 is a detail elevation of the main feed-dog showing the loop-controlling comb mounted thereon. Fig. 9 is a bottom plan view of the throat-plate. Fig. 10 is an end elevation of the work-supporting arm showing the needles and looper in front elevation and the throat-plate in transverse vertical section. Fig. 11 is a plan view showing the loop-controlling comb in its relation to the needles, looper and feed-dogs. Fig. 12 is a longitudinal section in the line of feed through the throat-plate and feed-dogs showing the comb in its forward or active position. Fig. 13 is a similar view at the period of the cycle when the descending needles are entering the looper-loop; the comb being in retracted or inactive position. Fig. 14 is an enlarged perspective view of the needles, looper and comb in the position shown in Figs. 10 and 12.

For the purposes of the present disclosure the invention is shown as embodied in the machine disclosed in my Patent No. 1,410,057, of March 21, 1922. This machine is formed with a frame including the base 1, standard 2 and work-supporting arm 3 within which the feeding and looper-actuating mechanisms are housed. The stitch-forming mechanism is of the well known multi-needle single-looper type and comprises the reciprocating needles 4 which cooperate with the looper 5 mounted on the rocking and sliding looper-shaft 6.

The feeding mechanism is of the differential type and comprises fulling and main

feed-dogs 8 and 9, respectively. Although any suitable four-motion feed-actuating mechanism may be employed, I prefer to use that disclosed in my said copending application. Secured to the main-shaft 7 is the feed-advancing eccentric 10 which is connected by the pitman 11 to the rocker-arm 12 the split hub 13 of which is clamped to the cross-shaft 14 to which shaft is also clamped the split hubs of the main feed-advancing rocker-arm 15 and the auxiliary feed-advancing rocker-arm 16. The rocker-arm 15 is formed with a curved slot 17 in which is adjustably secured a pin 18 connected to one end of a link 19 the opposite end of which is pivotally connected to a lever 20 depending from a fixed fulcrum-pin 21 which extends across and within the standard 2 in parallelism with the main shaft 7. The lower end of the lever 20 is pivotally connected to the rearward end of the main feed-bar 22 which extends within and longitudinally of the work-arm and, at its forward end, carries a screw-pin 23, Fig. 8, which passes through the slotted shank 24 of the main feed-dog 9 and serves to secure the latter to said bar while permitting adjustment of the feed-dog lengthwise of said bar. The height of the main feed-dog is determined by the position of adjustment of the slotted wedge 25 which is placed between the feed-bar 22 and the shank 24.

The auxiliary feed-rocker 16 is formed with a curved slot 26 in which is fitted a pin 27 carried by the rear end of a link 28 the front end of which is pivotally connected to a lever 29 depending from the fulcrum-pin 21. The lower end of the lever 29 is pivotally connected to one end of a link-section 30, the opposite end of which carries a fixed pin 31 and a screw 32, both extending through the slots 33 in the rear end of the link-section 34, the front end of which is pivotally connected at 35 to a bracket 36 screwed to the side of the auxiliary feed-bar 37 which is deeply recessed or grooved at its under side, Fig. 2, to fit about and slide upon the forward end-portion of the main feed-bar 22. The feed-bar 37 carries the auxiliary feed-dog 8. The fulling feed may be readily adjusted while the machine is in operation by means of the feed-controlling lever-arm 38 which is mounted on the rock-shaft 39 fulcrumed in the standard 2. The lever-arm 38 is connected by the link 40 to the link 28.

The main and auxiliary feed-bars are supported within the work-arm on a fulcrum-block 41 which is fitted within the slot 42 in the main feed-bar and is carried by the fulcrum-pin 43 supported, in turn, at the forward end of the feed-lifting lever 44 which is pivoted within the work-arm on the trunnion-screws 45, 45. The feed lifting lever

44 is rocked by means of the eccentric 46, carried by the main-shaft and embraced by the upper strapped end of a pitman 47, the lower end of which is pivotally connected to a rearward extension 48 of said feed lifting lever. 70

The looper-shaft may be actuated by any usual or suitable mechanism. For example, the looper-shaft 6 may be fitted at its rearward end with a crank-arm 49 having a bellcrank-pin 50 which is embraced by the lower strapped end of a link 51 the upper strapped end of which embraces a ball-eccentric 52 on the main-shaft 7 which imparts loop-seizing and -shedding movements to the looper. The hub of the crank-arm 49 is formed with a rearward extension carrying a ball-ended pin 53 disposed concentrically with the axis of the looper-shaft and embraced by the socketed end of a link 54 whose opposite end is connected to the depending arm 55 of a rock-lever fulcrumed to oscillate upon and independently of the cross-shaft 14 journaled in the standard 2. The upwardly extending arm 56 of said rock-lever is slotted at 57 to receive an adjustable pin 58 which, through the pitman 59, connects said lever with the eccentric 60 carried by the main shaft; said eccentric serving to impart sidewise or "needle-avoiding" movements to the looper. The feed-dogs rise and fall through slots 61 in the throat-plate 62 which is mounted at the free end of the work-supporting arm 3 and is formed with the usual needle-apertures 63 and chaining-off fingers 64. The usual presser-foot 65 operates to hold the work on the throat-plate and to supply the necessary yielding pressure to enable the feed-dogs to effect their functions. 95

In the particular embodiment of the invention illustrated, the needle-loop controlling device is in the form of a comb 66 having a series of projections or teeth 67 which are spaced apart a distance equal to the spacing of the needles 4 and are directed toward the needles in opposition to the direction of feed. The teeth 67 of the comb are adapted to be projected forwardly between the needles, as shown in Fig. 14, at the period of the cycle when the needles are rising to throw out their loops. At this time, the teeth 67 guide the expanding needle-loops and hold them in parallel planes broadside of the path of the advancing looper, thus preventing the loops from twisting around sidewise and escaping seizure by the looper. The teeth 67, being positioned at this time above and close to the upper edge of the looper, also act to prevent the looper from dragging a seized needle-loop into an expanded or newly formed needle-loop about to be seized. 110

The comb 66, if retained in its advanced position, will interfere with the drawing up 125

of the stitches and must therefore be retracted to an ineffective or out of the way position before the descending needles pass their respective previously formed loops on the looper. While any suitable mechanism may be used for imparting advancing and retracting movements to the comb 66 at the times specified, I find it convenient and desirable to mount the comb rigidly upon a short forward extension 68 of the main feed-dog 9, as shown in Fig. 12. When fixed to the feed-dog, it is found that the comb will receive the desired motions at the times above indicated without the need of further actuating mechanism.

It is sometimes found desirable to employ a guard 69 for covering the teeth of the comb 66 when the latter is in retracted position. This guard may be made up in the form of a light bar secured at one end to the throat-plate by means of a screw 70 and at its opposite end formed with a T-head 71 extending transversely of and slightly below the chaining off fingers 64. This guard will prevent the needle-loops from catching on the teeth of the comb and will also serve as a stripper to free the teeth from any threads which may be caught thereby.

The timing is as follows:

As the needles rise to throw out their loops, the feed-dogs occupy their forward positions, Fig. 12, and are rising into engagement with the work. The teeth or projections 67 are thus positioned between the needles and just clear the top edge of the looper 5 as the latter advances, as shown in Figs. 10, 11, 12 and 14. As soon as the looper has seized the needle-loops and the needles leave the fabric, the feed-dogs begin their feeding stroke, thus withdrawing the teeth of the comb from their positions between the needles. After the feed-dogs have executed their feeding stroke, the comb will have been withdrawn to a position beneath the head 71 of the guard 69, as shown in Fig. 13. The needles then descend and pass their respective previously formed loops on the looper, which loops shall preferably be closely controlled, as disclosed in my said copending application, in order that said loops will assume evenly spaced positions on the looper at this time. When the needle-loops are shed by the looper they are successively drawn up to the work by the take-up mechanism.

I prefer to depend entirely upon the refinement of needle-thread control and the shape of the looper-blade to insure an even spacing of the needle-loops on the looper after they have been seized by the looper, as explained in my said copending application; the present improvement being designed not to hold the needle-loops apart after they have been seized by the looper-blade but

primarily to prevent twisting of the expanding needle-loops prior to their seizure by the looper and, secondly, to prevent the looper from dragging a seized needle-loop into an adjacent needle-loop about to be seized.

The invention, in certain of its aspects is not peculiar to multiple-needle machines but is useful in single-needle machines, as will be obvious to those skilled in the art from the foregoing disclosure. It is well known that the direction in which a newly formed needle-loop tends to twist depends upon the twist of the thread used, i. e., whether of right or left hand twist. It will therefore be evident that the loop-controlling projection can be placed on either side of the needle, depending upon the twist of the thread used.

Having thus set forth the nature of the invention, what I claim herein is—

1. In a sewing machine, in combination, a plurality of spaced needles, a single looper cooperating therewith to form stitches, a needle-loop guide having one or more projections adapted to extend between the needles, and actuating means for said guide timed to move said projections between said needles to guide the newly formed needle-loops during the first part of the up-stroke of the needles and to withdraw said projections from between the needle paths prior to the entry of the needle points into the looper-loop, thus permitting the needle-loops to be drawn up to the work as they are shed by the looper.

2. In a sewing machine, in combination, a reciprocating needle, a looper operating transversely of the line of feed and cooperating with the needle to form stitches, a four-motion feed, and a reciprocating needle-loop guide deriving movement from said feed and located above the lowest position of the needle-eye.

3. In a sewing machine, in combination, a plurality of reciprocating needles, a looper cooperating therewith to form stitches, a four-motion feed, and a needle-loop guide mounted in rear of said needles and above the lowest position of the needle-eyes and deriving movement from said feed, said guide operating to prevent twisting of the needle-loops as they are thrown out by the needles preparatory to seizure of said loops by the looper.

4. In a sewing machine, in combination, a reciprocating needle, a looper operating transversely of the line of feed and cooperating with the needle to form stitches, a four-motion feed-dog, and a loop-controller connected to move back and forth with said feed-dog and having one or more projections adapted to extend alongside said needle at a level above the lowest position of the

needle-eye to guide the expanding needle-loop when the feed-dog is at the beginning end of its feeding stroke.

5. In a sewing machine, in combination, a plurality of needles set in a plane crossing the line of feed, a single looper cooperating therewith to form stitches, a throat-plate, a needle-loop guiding comb mounted below the throat-plate, and actuating means for projecting one or more of the teeth of said comb between the needles to guide the expanding needle-loops prior to their seizure by the looper.

6. In a sewing machine, in combination, 15 a plurality of needles set in a plane crossing the line of feed, a single looper cooperating therewith to form stitches, a throat-plate, a needle-loop guiding comb mounted below the throat-plate, and actuating means for 20 projecting one or more of the teeth of said comb between the needles to guide the expanding needle-loops prior to their seizure by the looper, said actuating means operating further to withdraw said teeth from the 25 plane of the needles prior to their descent into the looper-loop.

7. In a sewing machine, in combination, a reciprocating needle operating to throw out a loop in a plane parallel to the line 30 of feed, a looper, a four-motion feed-dog having feeding teeth in rear of said needle, and a needle-loop guide mounted on said feed-dog below the level of the feeding teeth and above the lowest level of the 35 needle-eye and projecting forwardly toward

said needle, said guide operating to hold the needle-loop in a plane transverse to the path of the advancing looper.

8. In a sewing machine, in combination, 40 a reciprocating needle, a looper, a reciprocating needle-loop guide including a projection moving from effective position alongside said needle to ineffective position remote from said needle, and a guard serving to cover said projection when the latter is 45 withdrawn from effective position.

9. In a sewing machine, in combination, 50 a reciprocating needle, a looper, a reciprocating needle-loop guide including a projection operating to prevent the newly formed needle-loop from twisting out of the path of the advancing looper, and a stationary guard for covering said projection when the latter is withdrawn.

10. In a sewing machine, in combination, 55 a throat-plate having a plurality of needle-apertures and intervening chaining-off fingers, a plurality of reciprocating needles, a looper cooperating therewith to form stitches, a reciprocating needle-loop guide 60 comprising a plurality of projections adapted to extend between the needles, and a guard mounted on said throat-plate and extending across and below the chaining off fingers, said guard operating to cover said 65 projections when the latter are withdrawn from between the needles.

In testimony whereof, I have signed my name to this specification.

GEORGE S. GATCHELL.
